APPARATUS FOR SUBJECTING CYLINDRICAL MEMBERS TO HEAT TREATMENT

Lee Wilson and Floyd Olmstead, Cleveland, Ohio, assignors to Lee Wilson Sales Corporation, Cleveland, Ohio, a corporation of Ohio

Application June 10, 1941, Serial No. 397,496

5 Claims. (Cl. 263—7)

This invention relates to a method and apparatus for progressively heating small objects and is of particular value in the metallurgical processing of articles such as shells, wrist pins or like objects which are either cylindrical or substantially so and therefore capable of rolling motion.

The heating of small articles has heretofore been attended with considerable difficulty from the standpoint of handling and more so in respect to the requirement that all the articles of a given batch be subjected to a uniform processing. We have invented a novel method and apparatus greatly simplifying the handling of small articles during processing and insuring that each article is subjected to the same processing conditions as all other articles.

In a preferred embodiment and practice of our invention, we provide a pair of elongated supports, preferably cylindrical or substantially so, disposed in closely spaced relation and mounted for rotation about their own axes. We arrange to supply heat to the articles on the supports, preferably from the interior thereof and rotate both supports in the same direction. The articles to be processed are delivered into the groove between the adjacent supports and are caused to rotate by their frictional contact therewith. The supports are preferably tilted so that the articles progress therealong by gravity. By appropriately designing the supports and controlling the amount of heat supplied to the articles traversing them, a wide variety of processing operations may be carried out.

Further novel features and advantages of the invention will be made apparent during the course of the following detailed description and explanation which refer to the accompanying drawings illustrating the preferred embodiment and practice outlined above. In the drawings,

Fig. 1 is a longitudinal vertical section through a heating apparatus or furnace according to our invention;

Fig. 2 is a partial plan view thereof with parts omitted; line I—I, of Fig. 2, indicates the plane on which the section shown in Fig. 1 is taken;

Fig. 3 is a transverse section taken along line III—III of Fig. 1; and

Fig. 4 is a similar section taken along IV—IV.

Referring in detail to the drawings, the apparatus of our invention includes a refractory-lined enclosure or furnace 10. The furnace 10 has a bottom 11, side walls 12, end walls 13 and a roof 14 composed of fire-brick and thermal-insulating brick disposed within sheathing plates

15 secured to structural frame members 16, 17 and 18. Adjacent one end, supporting legs 19 are secured to the frame members 17. The legs 19 are provided with rocker feet 20. Adjacent to the other end of the furnace, an adjustable support is provided in the form of a jack screw 21. A cross beam 22 is disposed between the members 17 and the jack screw 21 and a similar beam 23 extends between the legs 19 and is secured thereto.

Cylindrical supports 24, preferably in the form of metal tubes, extend longitudinally of the furnace 10 in closely spaced, parallel relation, and have reduced end portions 25 and 26 projecting through suitable openings in the end walls 13. The spaces between the reduced end portions of the tubes and the furnace walls are closed by packing glands 27 and 28.

The tubes 24 have journal portions on the reduced ends thereof which are received in bearings 29. The bearings are carried on cross channels 30 extending between the frame members 17. Driven sprockets 31 are secured to the reduced end portions 25 of the tubes 24. A chain 32 trained over the sprockets 31 traverses a driving sprocket 33 on the low speed shaft of a motor-reducer unit 34. By the arrangement shown, operation of the unit 34 causes the tubes 24 to be driven in the same direction, i. e., either clockwise or counter-clockwise.

The tubes 24 are heated interiorly. While any convenient form of heating may be employed I prefer to utilize burners 35 projecting into the reduced end portions 25 of the tubes, for supplying fuel for combustion within the tubes 24 to heat them by direct contact of the combustion gases therewith. The burners 35 are connected to a manifold 36 through manually adjustable control valves 37. A fuel supply pipe 38 connects the manifold 36 to a suitable source of fuel.

Air for supporting combustion within the tubes 24 is supplied to the latter from an air chest 39. The reduced ends 25 of the tubes 24 extend through a side wall of the chest 39 and have a rotatable connection thereto sealed by rings 40. An air supply pipe 41 extends from the chest 39 to a suitable source of air under pressure such as a motor-driven blower. Valve plates 42 are adjustably mounted in the chest 39 and overlie the openings through which the reduced ends 25 of the tubes 24 extend whereby they control the volume of air flowing from the chest into the several tubes.

55 It will be understood that when fuel is supplied

through the burners 35 and air is maintained at suitable pressure in the chest 39, the valve plates 42 being appropriately positioned, the resulting combustible mixture delivered to the interior of the tubes may be ignited at the discharge end thereof whereupon combustion continues within the tubes so long as the supply of air and fuel is maintained. The combustion gases traversing the tubes 24 heat them quickly to a high temperature whereby the articles being processed are in turn heated by direct contact with the exterior of the tubes.

The reduced ends 28 of the tubes 24 extend into an exhaust box 43 and have a rotatable connection therewith, the latter being sealed by rings 44. The box 43 is connected to a stack or other suitable outlet for spent combustion gases.

The articles, for the processing of which our invention is particularly adapted, are indicated at 45, and as shown, are cylindrical and relatively short. The articles are delivered into the grooves between adjacent tubes 24 by delivery chutes 46 extending from a magazine shown diagrammatically at 47 having a removable cover 47A, through the adjacent end wall 48 of the furnace 10. The magazine and chute are charged at intervals, the magazine being kept closed between charging operations. As indicated in Fig. 1, the furnace is bodily tilted at a slight angle to the horizontal by appropriate adjustment of the jack screw 21. This adjustment of the furnace causes the articles 45 to travel longitudinally of the tubes 24 as the latter are rotated. The articles themselves are similarly rotated because of their frictional contact with the tubes, the direction of the rotation of the tubes and articles being indicated by arrows in Fig. 4.

Discharge chutes 48 are positioned to receive the articles after they have traversed the length of the central portion of the tubes 24. The chutes 48 extend downwardly through one end wall of the furnace 10 and deliver the articles into a quenching bath 49. The reduced ends 25 and 26 of the tubes 24 are connected to the central portions of the latter by frusto-conical sections 50. When the articles reach the sections 50 of the tubes 24, the leading end drops downwardly because of the divergence between the walls of the adjacent tubes, thereby permitting the articles to fall directly into the mouth of the chutes 48. Successive articles are separated by this operation, by the interval between the discharge of one and the approach of the next to the discharge position. This avoids bumping of one part by another and the damage which might result, particularly if the articles are threaded.

A conveyor 51 has its lower end disposed in the bath 49 below the chutes 48 and is effective to carry the articles delivered therethrough upwardly and out of the bath to a discharge chute 52. The conveyor 51 may conveniently be of the apron type, composed of cross slats secured to endless belts or chains and having flights 53 thereon. Guides 54 and 55 determine the path of the lower and upper runs of the conveyor respectively. The travelling element of the conveyor is trained around sheaves 56 and 57.

The conformation of the chute 48 delivers the articles to the conveyor 51 in a position the reverse of that which they occupy on the supports 24. This is particularly desirable if the articles are hollow since it facilitates drainage of the

quenching fluid as the articles are removed from the bath.

It will be apparent from the foregoing description and explanation that the invention provides a method and apparatus for uniformly heating rollable articles by direct contact, which are simple in operation and construction and relatively inexpensive to construct and maintain. It will be evident that since the articles being processed are constantly rotated in contact with the cylindrical heating tubes, heat is delivered substantially uniformly over the exterior of the articles and each article is subjected to precisely the same heating effect as all the others, assuming that the tubes 24 are driven at a constant speed, that the firing rate of the burners is not changed and the angle or inclination of the tubes remains the same. Variations in any of these factors may be utilized to control the final temperature to which the articles are raised. The angle or inclination of the tubes is preferably adjusted so that the travel of the articles thereon will be relatively slow, thus insuring a gradual heating-up. By adjusting the slope and speed of the supports 24, an infinitely variable speed of travel of the articles therealong is obtainable. It will be apparent that the lower end of the delivery chute 46 will normally be at a relatively high temperature so that the heating of the articles commences before they are delivered onto the tubes 24.

A further advantage of the invention is that the articles move unidirectionally through the apparatus in a continuous stream. The thermal efficiency of the method and apparatus is quite high because of the intimate contact of the work pieces or articles being processed with the supporting tubes 24, and the heating of the articles is rapid as well as uniform. Another advantage is that the work pieces are not subject to contact with the combustion gases. This permits the use of special atmospheres in the furnace 10, e. g., a non-oxidizing or reducing atmosphere in case bright annealing is being carried on. The packing glands 27 and 28 prevent loss of such special atmosphere by way of the holes in the furnace walls through which the ends of the tubes project. The articles fit the chute 46 fairly closely and the magazine 47 is normally closed. The chute 48 discharges under the surface of the quenching bath. Loss of the special atmosphere through the feed and discharge chutes is thus limited or prevented.

A furnace according to our invention may be designed with any desired number of supporting tubes. The arrangement shown in the drawings, utilizing three tubes, has the maximum capacity per tube, since the middle tube cooperates with each of the outside tubes in supporting a row of work pieces.

Although we have illustrated and described in detail a preferred embodiment of our invention, it will be recognized that changes in the construction and operation disclosed may be made without departing from the spirit of the invention or the scope of the appended claims.

Instead of delivering a combustible mixture to the interior of the supporting tubes and causing combustion therein, the tubes may be otherwise heated internally, as by electric resistance heaters, or heat may be supplied on the outside of the tubes by burners discharging into the interior of the furnace or electric resistance heating element suitably mounted therein. Instead of the tubes 24, the elongated supports for the

articles being processed may be solid. They may, furthermore, be composed of refractory material instead of metal.

The gravity feed of the articles along the support may be dispensed with and any suitable form of feed means employed which is capable of operating between the tubes 24 or other supports similar thereto. In the processing of spherical articles such as balls, it is undesirable to have the tubes slope downwardly toward the discharge end because this would permit the balls to roll freely down the supports in such a short time that proper heating thereof could not be obtained. In such cases, the supporting tubes may be tilted upwardly toward the discharge end by lowering the jack screws 21 and the articles pushed along the tubes either by pressure applied to the rearmost article in the magazine and feed chute or by a special travelling feed mechanism. For example, a spiral flight on one of the tubes would suffice to advance the articles therewith in a positive manner at a predetermined rate. A travelling feed chain is another example of means suitable for urging several articles along the tubes if they are tilted up toward the discharge end or restraining them from too rapid passage along the tubes if they are tilted downwardly toward the discharge end.

It will be understood, furthermore, that the supporting tubes 24 need not be precisely parallel nor truly cylindrical. Tapered rolls may be useful for certain types of articles and the rolls may be set at a slight angle as well as exactly parallel.

It will be evident that the invention may be used for the heating of a wide variety of articles either spherical, truly cylindrical, or irregularly shaped, i. e., tapered, headed or the like as are many forms of pins, screws, rivets, etc.

We claim:

1. A heating furnace comprising a refractory-lined enclosure, a pair of inclined tubes extending through the furnace, journal bearings out-

side the furnace engaging the ends of the tubes and supporting them rotatably in closely spaced, generally parallel relation, means supplying heat to the interior of said tubes, a delivery chute, adapted to direct work pieces into the groove between said tubes near one end thereof and a discharge chute near the other end of the tubes adapted to receive the pieces after they have traveled along the tubes.

5 10 2. A heating furnace comprising a refractory-lined enclosure, a pair of tubes extending through the furnace, journal bearings outside the furnace engaging the ends of the tubes and supporting them rotatably in closely spaced, generally parallel relation, and burners firing into said tubes through one end thereof.

15 20 3. A heating furnace comprising a refractory-lined enclosure, a pair of tubes extending through said enclosure in closely spaced, generally parallel relation, means mounting said tubes for rotation about their own axes, means for driving said tubes, means for heating said tubes, and means for bodily tilting said enclosure about an axis transverse to the axis of said tubes to cause work pieces placed in the groove between said tubes near one end thereof to travel along said tubes as the latter are rotated.

25 30 4. A heating furnace as defined by claim 3 characterized by said tilting means including supporting legs with rocker feet near one end of the enclosure, and an adjustable support for other end of the enclosure.

35 35 5. Apparatus for conveying articles through a heating zone comprising a pair of substantially cylindrical supports mounted for rotation in said zone, said supports being frusto-conical at least adjacent one end whereby the increasing divergence between the surfaces of the supports at said end facilitates the discharge of articles moving along said members.
